UNITED STATES PATENT OFFICE.

GEORGE W. WHITTINGTON, OF INDIANAPOLIS, INDIANA.

WIRE-FENCE-WEAVING MACHINE.

SPECIFICATION forming part of Letters Patent No. 629,637, dated July 25, 1899.

Application filed September 19, 1898. Serial No. 691,360. (No model.)

To all whom it may concern:

Be it known that I, GEORGE W. WHITTINGTON, a citizen of the United States, residing at Indianapolis, in the county of Marion and State of Indiana, have invented new and useful Improvements in Wire-Fence-Weaving Machines, of which the following is a specification.

My invention relates to certain improvements in wire-fence-weaving machines; and it consists in a mechanism of peculiar construction and operation to produce wire fencing the meshes of which shall be of half-diamond shape or approximately triangular in form, the juncture at the corners of each mesh being formed of three wires, two of which are twisted around the third wire in such manner as to firmly connect with same, and thus prevent distortion or change of shape of the meshes so constructed.

The invention further consists in certain combinations and arrangements of parts, all of which are hereinafter fully described and specifically claimed.

In the accompanying drawings similar numerals designate like parts in all the figures.

Figure 1 is an end elevation of the machine, showing the driving mechanism thereof. Fig. 2 is an elevation of the opposite end of the machine, with its reciprocating mechanism for operating the drag-plates of the spool-carriers. Fig. 3 is a detail view showing a plan of the reciprocating mechanism of the drag-plates. Fig. 4 is an enlarged transverse sectional elevation of the spool-carriers and their rotating mechanism, taken through the line A B of Figs. 5, 7, 10, 11, and 13. Fig. 5 is a sectional plan view at E F of Fig. 7, showing the drag-plates whereby the spool-carriers are moved alternately from one revolver to another and represents the said plates in their extreme positions after moving in the direction indicated by the arrows. Fig. 6 represents the drag-plates in their extreme opposite positions. Fig. 7 is a longitudinal section through the line C D of Fig. 6, showing the lower guide and the supporting-beam in which the lower drag-plate operates and showing the relative positions of the spool-carrier revolver. Fig. 8 is a detail view showing in elevation one of the wire-twisters. Fig. 9 is a like view showing the wire-receiving

slots and the spool-carrier guideways. Fig. 10 is a plan view of a portion of the upper guide-beam, with slots connecting the wire-receiving slots of each consecutive wire-twister, through and by which the wires are alternately moved back and forth from one wire-twister to its adjacent wire-twister. Fig. 11 is a plan view of the lower guide-beam, with guideways by and through which the base-guide strips or bars of the spool-carriers slide and are guided during the movement of the spool-carriers from their revolvers to the revolvers next thereto. Fig. 12 is a detail view, in side elevation, of a spool-carrier revolver. Fig. 13 is a detail view showing the guideways wherein the guide bars or strips of the spool-carrier rest. Fig. 14 is a broken sectional view of the lower guide-beam, taken through the line G H of Figs. 7 and 11. Fig. 15 is a perspective view of one of the marginal wire tension or stretching pinions for holding the marginal wires of the fence during the weaving process, and Fig. 16 represents the manner in which the fence-wires are secured together and the style of "mesh" produced.

The frame of the machine is composed of two end pieces 1 and 2, a connecting rear beam, shown by dotted lines at 3, (see Figs. 1 and 2,) the said connecting-beam secured by bolts, as shown at 4, and the upper and lower drag-plate-supporting beams, (marked, respectively, 5 and 6,) the former, 5, having its ends secured to the top of the end pieces 1 and 2 and the latter, 6, secured to the inside supporting-brackets 6^b of said end pieces by means of bolts, as shown at 7.

The frame end 1 is provided with a projecting stud 9, on which is journaled a driving-pulley 8, having an inwardly-projecting hub 10, to which is keyed or otherwise secured a drive-pinion 11 to engage a gear-wheel 12, formed on the inner face of the disk of a mutilated bevel gear-wheel 13, secured on the shaft 14, so as to rotate with same in the direction indicated by the arrow. The said wheel 13 is designed to rotate continuously and to intermittently rotate the bevel-pinion 15 and its shaft 16. The relative proportion of the aforesaid wheel and pinion are such that while the wheel makes one-half of a revolution the pinion will make two complete

revolutions, when by reason of the toothless portion of the wheel being presented to the pinion the latter ceases to revolve. In order that the pinion 15 and its shaft 16 and all the 5 operating mechanism connected therewith and deriving motion therefrom be held at rest during the period of the disengagement of the aforesaid gear, one end of the shaft 16 is provided with a square or rectangular flat- 10 sided piece 17, which is adapted to be engaged by a semicircular cam 18, formed on one face of the gear-wheel 13 during the period of rest. The cam 18 commences to engage the block 17 as the last tooth of the mutilated 15 gear 13 is disengaged from the pinion 15, and the said block 17 begins to disengage with the cam as the first tooth of the mutilated gear begins to engage the pinion 15.

The shaft 16 is journaled in boxes 19 on 20 the outer side of the frame end 1. On one end of this shaft is secured a spur-pinion 20 to engage a spur-wheel 21 of a shaft 22, having journal-bearings in boxes 23. The ratio of the diameters of the pinion and wheel is 25 preferably one to four, that the pinion may make two revolutions to a one-half revolution of the wheel during one period of time and during the next equal period be at rest. Thus the said mechanism operates continuously so 30 long as the driving-pulley 8 is rotated.

The wheel 21 is provided with a crank-pin 24, from which motion is imparted through a connecting-rod 26 to a reciprocating block 25, the said block being provided for said purpose with a journal-pin 29. The connecting-rod 26 is formed in two parts with a screw-coupling connection to permit of a proper adjustment of the reciprocating block 25, the latter adapted to operate in guideways 27, 35 having removable caps 28 to permit of the withdrawal of the said blocks when in need of repair. The pin 29 of the reciprocating block has a reduced inner end 30, adapted to project through a slot 31, formed in the side 40 of the drag-plate-supporting beam 6 and into the rack 33, to which its reciprocating motion is imparted.

For convenience in handling the rack 33 is composed of a series of sections placed end 50 to end and in perfect alinement, and thus securely riveted between an upper and a lower guide-strip, (marked, respectively, 35 and 36.) The edges of these strips are planed truly, and the edges which are next the teeth project to a sufficient extent to overlap the engaging teeth of the spool-carrier-rotating pieces 34 and to bear against the top and bottom cylindrical portions of same. Thus they serve to insure a proper meshing of the teeth, while at 55 the same time they prevent the rotating pieces from "climbing" or moving upward on their bearing-studs 37, the latter vertically secured in the trough of the beam 6 at such relative distance apart as the style of meshes may require.

An axial hole 38 is drilled longitudinally

through the rotating pieces 34 for the passage of the running wires of the fencing, around which the other wires of the fencing are twisted and secured, as hereinafter more 70 fully described.

The top surfaces of the rotating pieces 34 are each provided with parallel grooves 39 to receive the bottom guide-strips 40, formed integral on the under surfaces of the journals 75 41 of the spool-carriers 42. The said journals have bearings in the drag-plates 43 and 44, while the upper journals 45 of the spool-carriers have their bearings in the drag-plates 46 and 47, and between each pair of opposing plates said spool-carriers are revolved, as indicated by the arrows in Figs. 5 and 6, either to the right or left to twist the wires around the running wires. The drag-plates and their operating mechanism will be hereinafter more 85 fully described.

The wire-twisters 48 (see Figs. 4 and 10) are journaled in the upper beam 5 and are equal in number to and directly above the spool-carrier revolvers 34, from which motion 90 is imparted to the wire-twisters through the spool-carriers 42. The base of each wire-twister 48 is provided with parallel grooves 95 49, which are adapted to receive the guide-strips 50, formed on the upper ends of the spool-carriers, by which means a coupling of the said parts is effected. The said wire-twisters 48 are also provided at opposite sides with vertical grooves or slits 51, (see Figs. 9 and 10,) so as to be in alinement with the wire-guide slots 52 after the wire-twisters have been rotated into position to permit the wire engaged by the twister 48^a to be transferred therefrom to the slot 51 of the twister 48^b. At the same time the next wire is passed 100 from the twister 48^b to the twister 48^a, and so on, according to the number of twisters employed in the machine. This interchanging of the wires is performed while the twisters 48 are at rest, during which time the woven-wire 105 fencing passes over the receiving-roller 53, under the tension-roller 54, and over the delivery-roller 55 to the reel 56, the latter operated by ratchet mechanism which is variable 110 and intermittent in its motion, as is herein- 115 after more fully described.

That end of the shaft 14 which has its bearing in the frame end 2 has a mutilated bevel gear-wheel 57 secured thereon, which it will be particularly observed is in mesh with and 120 has revolved a pinion 58 one-fourth of a revolution or one-half the required rotation to be made thereby during one period of time, while the pinion 15 at the opposite end of the frame is at rest and has been at rest one-half 125 of its period of motion or during the quarter of a revolution of the shaft 14. The reason for this movement will be hereinafter more readily understood.

The mutilated bevel gear-wheel 57, like its 130 opposite and companion wheel 13, is provided with a cam 59, adapted to engage the flats 60,

formed on the opposite sides of the hub of the bevel-pinion 58 to retain said pinion and its shaft 61 at rest.

The vertical shaft 61 is journaled in the joint-bearings 62 of the end frame 2 and has a supporting-collar 61^c, by which either a vertical or longitudinal movement of said shaft is prevented.

The upper end of shaft 61 is provided with a crank 63, having a pin 64 to receive one end of a connecting-rod 65, the opposite end of said rod being connected with the forked end of a lever 66 by a pin 67. The lever 66 is keyed or otherwise secured to a rock-shaft 68, on which is also secured the top and bottom arms 69. The said rock-shaft is journaled in the upper and lower bearings 70, which are connected with the frame end 2 by means of bolts, as shown at 71.

20 The upper drag-plates 46 47 and the lower drag-plates 43 44 are respectively connected with the oppositely-projecting top and bottom arms 69 by connecting-rods 72 and 73, through which motion is imparted to the drag-plates, so that the top plates 46 and the bottom plates 43 shall traverse simultaneously in one direction, while the upper drag-plate 47 and the lower drag-plate 44 shall traverse simultaneously in the opposite direction.

25 Referring to Fig. 5, it will be seen that the set of plates 43, 43^a, and 43^b are represented as having traversed their full extent to the left and are at rest, while the drag-plate sections 44, 44^a, and 44^b have traversed their full extent to the right and are also at rest. This movement of the plates causes a transposition of the spool-carriers 42. For example, the spool-carrier 42 has been transferred from the rotating piece 34^m to the rotating piece 40 34^l, (see also Fig. 7,) and in like manner have the rest of the spool-carriers in this row been transferred to their adjacent rotating pieces. Similarly the spool-carrier 42 on the opposite row is transferred from the rotating piece 34 to the rotating piece 34^a and all the remaining spool-carriers in this row are transferred to the rotating pieces next thereto, as shown in Fig. 5. This transposition of spool-carriers 42 causes the wires from the spools 74 to 45 cross each other and likewise to cross the straight or parallel wires of the fencing. It also causes the said cross-wires to be moved into the slits of their respective twisters to be wound or twisted together—that is, (see 50 details, Figs. 10 and 16,) out of the slots 51 of the twister 48^a along the slot 52 into the slot 51 of the twister 48^b and simultaneously from the slot 51 of 48^b along the slot 52 into the slot 51 of the twister 48^c and so on throughout the 55 row of twisters.

The distances between each pair of rotating pieces 34 are variable or unequal, the space between each pair of spool-carriers corresponding with the size of the meshes required in the fencing. In this case the meshes gradually diminish in depth toward the bottom edge of the fencing, as will be seen on refer-

ring to Figs. 5 and 6. The distance, therefore, of each of the drag-plates 44^b, 44^a, and 44 and the drag-plates 43^b, 43^a, and 43 will necessarily be different the one from the other. To accomplish this object, I provide means to produce "lost motion" between each of the plates, as will be now described. The said means consists of strips or bars of metal 75 and 76, which are fitted in grooves formed in the drag-plates 44, 44^a, and 44^b and the drag-plates 43, 43^a, and 43^b. The strip or bar 75 is securely riveted at one end to the plate 43^b only, and the remaining portion of 80 said strip or bar works freely in the grooves of the drag-plates 43^a and 43^b. A stop-pin 77 engages the end of the drag-plate 43^a after the drag-plate has traversed a distance equal to the difference between said plate 43^b and 85 the lesser distance to be traveled by the plate 43^a, and another stop-pin 78 is riveted or otherwise secured to the said strip 75 to engage the end of the drag-plate 43 when the difference of the travel between the now remaining distance to be traversed by the plate 43^b and the lesser distance to be traveled by the plate 43 is reached, and this last plate is therefore traversed a distance equal to the entire movement of the plate 43^b less the sum 90 of the lost motion between the adjacent and abutting plates. It will also be readily understood on referring to Fig. 5 that the plate 44^b has traversed the full distance of the throw of the rocker-arm 69 without lost motion and that the plates 44^a and 44 have traversed the same distance as the plates 43^a and 43, but in an opposite direction to same.

The relative positions of the aforesaid plates after traversing in an opposite direction to that above described is shown in Fig. 6 and needs no further description.

The drag-plate sections are each provided with elongated slots 80, through which project pins 79 for the purpose of retaining the plates in position when at the end of their strokes as well as to serve as guides for same when in motion.

Referring to Fig. 2, the reel 56 is provided with arms 81, which are pivotally connected at their inner ends with the inner sides of the reel-disks. The said disks are also provided with stops 82, against which the arms contact when the reel is rotated in the direction indicated by the arrow. The ends of the 110 arms on the opposite end of the reel-shaft 83 support angle-iron rails 84, upon which the fencing is wound.

For convenience in removing the fencing from the reel the latter is adapted to be withdrawn from its frame, when by turning the shaft 83 in the direction indicated by the arrow *b* the pivotal points of the arms 81 are removed, which action causes the angle-bars 84 to be brought closer together, thus reducing 125 the diameter of the reel, that the fencing may be the more easily removed therefrom.

A ratchet-wheel 85 is secured on the reel-shaft 83, and a lever 86 is loosely fitted on the

said shaft between the ratchet-wheel and the frame end 1. This lever is provided with one or more pawls 87, adapted to operate on pins 88, so as to engage the teeth of the ratchet-wheel. When more pawls than one are used, their lengths are made to vary, so that only one of the pawls will engage the teeth of the wheel at one time when it becomes necessary to impart a rotation to said wheel less than the pitch of the ratchet-teeth. Suitable pawls 89 are pivotally connected with the frame end 1 and provided with gravity-weights for the purpose of retaining the said pawls in engagement with the teeth of the wheel 85.

15 A connecting-rod 89, having one of its ends fitted on the crank-pin 90, secured to the face of the mutilated bevel gear-wheel 13, is provided at its opposite end with a pin 91, which is adapted to operate in the slot 90 of the 20 rocking lever 86.

25 Radial arms 93 are pivotally mounted on the shaft 14, carrying at their free ends the roller 94, which extends from arm to arm over the reel and is adapted to contact with the 30 fencing as it is being reeled. Thus as the diameter of the roll increases the ends of the arms ascend and carry with them the arm 95, which is provided with a segmental slot adapted to receive the prolonged end of the 35 pin 88, which is therefore elevated in the slot 92, and the amount of rotation of the ratchet-wheel 85 is reduced. Consequently the reel is proportionately diminished, and so as the 40 fencing is reeled to increase its diameter a proportionate reduction of the amount of the rotation of the ratchet-wheel 85 is caused to compensate for the increased diameter of said reel.

45 The foot of the arm 95 is preferably made segmental in form in order to fit into the segmental groove of the arm 93, and the said form of construction is provided for the purpose of permitting the arm 95 to be either raised or lowered to decrease or increase the 50 amount of the rotation of the reel and to adjust the same to adapt the feed to the different grades of coarseness or fineness of the wires of which the fencing is composed.

55 In order to prevent creeping or distortion of the outer straight or marginal wire of the fencing while under construction, I provide the tension-pinions 96, having teeth 97, the said teeth inclined on their bearing or outer sides for the purpose of counteracting the tendency 60 of the marginal wires from being drawn inwardly by the cross-wires during the operation of twisting. Thus they operate to retain said wires in alinement.

65 The rollers 96 are arranged in pairs at each marginal wire of the fencing and are supported in the journal-bearings 98 and 99 at the top of the beam 5.

70 The receiving-roller 53 is journaled in brackets 100, which are bolted to the ends of 65 the top beam 5. This roller is preferably composed of the end disks 53, secured on the shaft 101, and peripheral round rods 102 are se-

cured at their ends to the said disks by suitable screw-nuts to support the fencing as it passes over same.

75 Having described my invention, what I claim as new, and desire to secure by Letters Patent, is—

1. A drag-plate for wire-fence-weaving machines, comprising a series of drag-plate sections, each section provided with a longitudinal groove, and a strip of metal adapted to fit the said grooves when the plates are in proper alinement, as described, the strip secured at one end, to one of the plate-sections 80 and the remaining part of the strip adapted to operate in the grooves of the other plates, the extent of said operation being limited by stop-pins connected with the strip, substantially as and for the purpose set forth. 85

2. In a wire-fence-weaving machine, the combination with a series of revolvers arranged in a single row, means for alternately rotating said revolvers and retaining them at rest, said means adapted to rotate said revolvers alternately in opposite directions, a series of spool-carriers arranged in opposite rows each of said opposing rows adapted to be traversed simultaneously in opposite directions, of a series of wire-twisters arranged 95 in a single row above said spool-carriers and in line with said revolvers, said wire-twisters adapted to be engaged by said spool-carriers to turn with said revolvers and said wire-twisters provided with wire-receiving slits or 100 notches formed vertically on their opposite sides and a conduit between each of the pairs of said wire-twisters and connecting the wire-receiving slits or notches thereof.

3. In a wire-fence-weaving machine, the combination with a series of toothed revolvers and a series of wire-twisters both of which are arranged in a single row each revolver having an axial opening or conduit, vertically-supported studs whereon said revolvers are 110 mounted, said studs drilled axially to form lower wire-conduits and connecting with said conduits of said revolvers, spool-carriers between said revolvers and said wire-twisters and means whereby said spool-carriers are 115 engaged by both said revolvers and said wire-twisters said twisters having notches adapted to receive the wires from the spools of said carriers, and a conduit between each of the pairs of wire-twisters and connecting the conduit slits or notches of each, of a reciprocating rack meshing with all the series of 120 revolvers and a suitable cam mechanism whereby said rack is alternately held at rest and traversed in alternate opposite directions. 125

4. In a wire-fence-weaving machine, the combination with a series of spool-carriers arranged in opposing parallel rows and each opposing pair having alternate motion of rotation in alternate opposing directions around 130 their axes, a period of rest, and a motion of translation at right angles with said axes and in alternate opposite directions, a series of wire-twisters above each of the pairs of spool-

carriers and adapted to be engaged by the latter to be rotated therewith, means for conducting the wires from the spools of their spool-carriers to the wire-twisters and means whereby a third wire is conducted vertically between said pairs of spool-carriers to said wire-twisters to be united and twisted with the spool-wires, of a receiving-roller above said twisters, a reel whereon the woven wire is wound and suitable means whereby said reel is rotated to wind said fence while said spool-carriers are at rest from rotation and during the period of the traversing of said

spool-carriers to cross the spool-wires and means as described whereby said reel is held 15 at rest while the spool-carriers are in rotation to twist the three wires at each of the points of juncture of the meshes of the fence.

In testimony whereof I have hereunto set my hand in the presence of two subscribing 20 witnesses.

GEORGE W. WHITTINGTON.
